PHONOGRAPH DISK RECORD CABINET

Wilbur H. Price, Cleveland, Ohio

Application October 8, 1941, Serial No. 414,170

8 Claims.

(Cl. 312—19)

The present invention relates to new and useful improvements in cabinets, and more particularly to a phonograph disk record cabinet, and has for its primary object to provide, in a manner as hereinafter set forth, a device of this character whereby a multiplicity of disk records may be stored and any one of which may be selected and ejected therefrom with a minimum of effort.

Another object of the invention is to provide a disk record cabinet wherein both the record selector and ejector have a common operating unit.

Another object of the invention is to provide an ejecting disk record cabinet which will be simple in construction, reliable in operation, and one which will be comparatively inexpensive to manufacture.

Still further objects and advantages of the invention will become apparent from a study of the following description, taken in connection with the accompanying drawings, wherein like character references designate corresponding parts throughout the several views, and wherein:

Figure 1 is a fragmentary front elevational view of a device embodying my invention.

Figure 2 is a plan view with parts broken away and shown in cross-section.

Figure 3 is a vertical transverse sectional view.

Figure 4 is an enlarged detail view of the ejector with parts broken away and shown in section.

Figure 5 is a fragmentary vertical sectional view taken substantially on the line 5—5 of Figure 2.

Figure 6 is a fragmentary vertical sectional view taken substantially on the line 6—6 of Figure 2.

Figure 7 is an enlarged detail view of the ejector moving member, and

Figure 8 is an enlarged perspective view in detail, of the ejector.

Referring now to the drawings it will be seen that the reference numeral 10 designates a box-like cabinet having a bottom wall 11, a top wall 12, end walls 13—13, back wall 14 and doors 15—15 which are adapted to swing on hinges 16. The cabinet may be supported in any suitable manner and is illustrated with supporting legs 17.

The bottom wall 11 is inclined from back to front as shown in Figure 3 of the drawings, and is provided with spaced record-receiving grooves 18 on its top side. The grooves 18 are of a sufficient depth to receive the plain edge portion 19 of the records 20 whereby the records are prevented from unintentional displacement by gravity.

A false top 21, the bottom side of which is inclined and grooved as at 22, is secured to the left end wall 13 and to the partition 12 in spaced relation to the top 12. Each of the grooves 22 in the false top 21 is in vertical alignment with the grooves 18 in the bottom wall 11.

To identify the records 20, in order to make a selection, a set of numbers or other indicia 23 is fixed on the front edge of the bottom wall 11 and a corresponding set of indicia 24 is fixed on the front edge of the false top 21.

A set of inserts or blocks 25, having grooves 26 and 27 in their top faces and bottom faces, respectively are removably mounted in the cabinet 10 with their grooved bottom faces engaged with the grooved top face of the bottom wall 11 and are held in position by the engagement of the grooves 27 and intervening ridges 28 with the grooves of the bottom wall 11. With the blocks 25 in position as described disk records of a diameter less than the distance between the false top 21 and bottom wall 11 may be housed in and ejected from the cabinet.

A plate or the like 29 is secured to the inner side of the back wall 14, intermediate the top and bottom edges thereof, to further guide and hold the disk records in vertical position. This plate 29 has spaced vertical shaped grooves 30 formed in its face for receiving the back edges of the records.

A substantially rectangular block support 31 is secured to the bottom side of the top wall 12 and is positioned between the back edge of the false top 21 and the back wall 14. This support 31 has a dove tailed groove 32 in its bottom portion 31 has a dove-tailed rib 34 thereon for sliding engagement in the dove tailed groove 32.

The kicker bar block 33 extends beyond the back side of the support 31 and is notched at one end portion as at 35. A kicker bar 36 is pivotally mounted intermediate its ends in the notch 35 on a pin 37 as best seen in Figure 8 of the drawings. The kicker bar 36 is held in inoperative position by a coil spring 38 which is mounted on the pin 37 with its end portion 39 held against movement by the kicker bar block 33 while its other end portion 39' engages the kicker bar 36 and forces it toward the back wall 14 of the cabinet 10 as shown in Figure 3 of the drawings. The bottom end portion or foot 40 of the kicker bar 36 is grooved as at 41.

The kicker bar 36 is moved into position be-

hind a selected record through the medium of a cable or cord 42, one end of which is anchored and wound several times around the side 43 of the spool 44. The cable 42 then extends over a pulley 45 which is supported on a shaft 46 secured to one end portion of the support 31. The cable 42 is secured at an intermediate portion to a stud 47 on the dove-tailed rib 34. From this anchored position the cable extends over a pulley 48 which is journaled on a pin 49 in the other end portion of the support 31. From the pulley 48 the cable 42 extends back through the dove-tailed groove 32 over a pulley 50 adjacent side 51 of the spool 43 about which it is wound several times and anchored thereto at its other end portion.

The spool 43 is loosely keyed on a shaft 52 which shaft 52 is rotatably and slidably mounted in openings in the bracket 53 and supporting arms 54—54 which bracket 53 and supporting arms 54—54 are secured to the top wall 12 and support 31, respectively, as clearly shown in Figure 5 of the drawings. The front end of the shaft 52 is provided with an operating knob 55. To prevent undesired forward movement of the shaft 52, I provide a stop in the form of a collar 53' about the shaft 52 which collar 53' is held in position rearwardly of the bracket 53 by means of a pin 53'' which extends transversely through the shaft 52.

A plate 56 is swingably supported on journals 57 and 58 and engage in apertured extensions 59 and 60 on the back side of the support 31 near its ends.

At one end of the plate 56 I provide a lever 61 the lower end portion of which is positioned rearwardly of the back end of the shaft 52. The plate 56 swings rearwardly against a spring 56A.

Partitions 62 and 63 conceal the shaft 52 and spool 43 in one end of the cabinet as shown in Figure 2 of the drawings.

The partition 63 has an opening 64 therein to permit passage of the knob 55 on inward movement of the shaft 52.

An indicator arm or pointer 65 is secured to the kicker bar block 33 at one end portion and extends from the block 33 over the false top 21 to indicate the selected disk record by means of its downwardly bent end portion 66.

The operation of the device is as follows. The indicator or pointer 65 is moved to a selected disk record 20 by turning the knob 55 on the shaft 52, which shaft rotates the spool 43 and transmits motion to the kicker bar block 33 to move it laterally in the support 31. As the kicker bar block 33 is operated it moves the pointer 65 to indicate the selected record. The kicker bar 36 is mounted on the block 33 in such a position as to be in alignment with the record indicated by the pointer 65. The knob 55 is now pushed inwardly forcing the inner end portion of the shaft 52 through the spool 43 thereby forcing the end of the shaft 52 to swing the arm 61, on the plate 56, toward the back wall 14 of the cabinet 10. The arm 61 swings the plate 56 which contacts and moves the top portion of the kicker bar 36 rearwardly and thereby forces the kicker foot 41 forward to eject one of the records 20.

Although I have shown and described herein a preferred form of my invention it is to be understood that any change or changes may be made in the structure and arrangement of the several parts, within the spirit of the invention as claimed.

Having thus described the invention, what I claim as new is:

1. In a device of the character described, a cabinet for holding disk records, said cabinet including means for holding records of various sizes, and means for ejecting said records and comprising a belt operated carrier having a kicker bar pivoted thereto.
2. In a device of the character described, a cabinet for holding disk records, record supporting blocks in said cabinet, and means for ejecting said records from said cabinet and comprising a belt operated carrier having a kicker bar pivoted thereto.
3. In a device of the character described, a cabinet for holding disk records means for supporting said records independently in said cabinet for individual ejection therefrom, and means in the cabinet for selecting and for ejecting said disk records and comprising a carrier having a kicker bar pivoted thereto, and a flexible operating member for the carrier.
4. In a device of the character described, a cabinet for holding disk records, record supporting blocks in said cabinet, and means for selecting and for ejecting said disk records and comprising a carrier having a kicker bar pivoted thereto, and a flexible operating member for the carrier.
5. In a device of the character described, a cabinet for holding disk records means for supporting said records independently in said cabinet for individual ejection therefrom, ejecting means in the cabinet for said disk records, said ejecting means including a pivoted kicker bar, record indicating means, a carrier for the kicker bar and indicating means said kicker bar being pivoted to the carrier, a flexible operating member connected to the carrier, and a rotatably and slidably mounted shaft operatively connected to the flexible member for actuating the latter in opposite directions upon rotation of the shaft, and means providing an operating medium between the shaft and the kicker bar for actuating the latter upon a reciprocating movement of the shaft.
6. In a device of the character described a cabinet for holding disk records, means in said cabinet for supporting said records independently for individual ejection from said cabinet, an ejector comprising a shaft, a knob on one end portion of said shaft, a spool loosely keyed on the other end portion of said shaft, a support for said shaft having a groove therein, a block having a rib thereon slidably engaged in said groove, a flexible drive member connecting the spool and block for actuating the latter in opposite directions upon a rotation of the shaft, a pointer on said block for indicating the record to be ejected, a kicker bar pivotally mounted on said block, and means for operating the kicker bar by manipulation of the shaft.
7. In a device of the character described, a cabinet for holding a plurality of disk records means for supporting said records independently in said cabinet for individual ejection therefrom, a kicker bar for ejecting one of said records from said cabinet, a pointer for indicating the record to be ejected, a carrier for the pointer and pivotally supporting the kicker bar, a track slidably supporting the carrier in the cabinet, a shaft operable in the cabinet and means operatively connecting the shaft to the carrier for actuating the latter, said shaft also being operatively con-

nected with the kicker bar for actuating the latter.

8. In a device of the character described, a cabinet for holding a plurality of disk records means for supporting said records independently in said cabinet for individual ejection therefrom, means in the cabinet for ejecting a record from said cabinet, a movable pointer for indicating the record to be ejected, a block, means slidably

supporting the block and said pointer, said ejecting means being carried by the block, a cable connected to the block for moving said block, a spool on which the cable is mounted, and means for turning said spool, said last-named means being movable independently of the spool and engageable with the ejecting means for actuating the latter.

WILBUR H. PRICE.
